(57) CLAIM

I claim the ornamental design for an ankle-foot orthotic, as shown and described.

DESCRIPTION

FIG. 1 is a top and left side perspective of an ankle-foot orthotic, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.
